UNITED STATES PATENT OFFICE.

WILLIAM MORRISON, OF LANSINGBURG, NEW YORK, ASSIGNOR TO EMMA MORRISON, OF SAME PLACE.

BRUSH-MOLD.

SPECIFICATION forming part of Letters Patent No. 532,210, dated January 8, 1895.

Application filed June 18, 1894. Serial No. 514,834. (No model.)

To all whom it may concern:

Be it known that I, WILLIAM MORRISON, a citizen of the United States, residing at Lansingburg, county of Rensselaer, and State of New York, have invented certain new and useful Improvements in Brush-Molds, of which the following is a specification.

The invention relates to such improvements and consists of the novel construction and combination of parts hereinafter described and subsequently claimed.

Reference may be had to the accompanying drawings and the letters of reference marked thereon, which form a part of this specification.

Similar letters refer to similar parts in both figures therein.

Figure 1 of the drawings is a central, vertical, longitudinal section of my improved mold. Fig. 2 is a view in side elevation of one of the plungers detached.

My invention relates to improvements in brush-molds for forming of plastic material the bristle-supporting head-block of a brush.

The object of my invention is to facilitate the removal of the brush from the mold without breakage.

The mold comprises the base-plate A—, and the crown-plate B—adapted to be superimposed upon the base-plate and held thereon in exact position by the dowel-pins C— which are supported by the base-plate and enter suitable apertures in the crown-plate.

The crown-plate is cut away on its inner side B'—to conform to the shape of the top surface and upper side edge of the molded portion of the brush. The walls of such inner side may be provided with any design, sunken or in relief, with which it is desired to ornament the back of the brush. The base-plate A—is similarly cut away on its inner side A'—to conform to the shape of the bottom surface and lower side edge of the molded article. The base-plate may also be provided with an ornamental design, when desired.

The base-plate is adapted for use in molding brushes by a plurality of bristle-sockets or recesses A²—arranged after the usual, or any known, method, and adapted to receive and support the bristles with their upper ends in the lower part of the mold cavity between the

two plates or mold-sections, in the usual well known manner. The base-plate is also provided with one or more apertures D—extending from the molding surface of the plate entirely through the same to its bottom surface. In each of these apertures, I insert a plunger D'—of suitable size to fit the aperture and adapted to be movable longitudinally therethrough. The inner end of the plunger is flush with the molding surface of the base-plate and such inner end has a molding face D²—corresponding with the molding surface of the base-plate around the aperture.

The operation of the device is as follows: The base-plate is first prepared by the insertion of bristles in the recesses A²—in the base plate, after which the bristles are trimmed so that their ends project uniformly into the mold cavity the distance it is desired to have them embedded in the brush-head. A small quantity of the plastic composition of which the brush is formed, may then be worked by hand between and around the projecting ends of the bristles to insure the complete embedding of such ends in the brush-head. The plunger or plungers D'—being in position, the mold cavity is then filled with the melted or partly melted composition which is rounded up in approximately the form of the completed brush; and the crown-plate superimposed thereon in the proper position determined by the dowel-pins. The mold is then complete, and is subjected to pressure in a press until the composition sets or hardens, whereupon the mold may be opened and the brush removed. The brush is removed from the base-plate by driving the plunger or plungers D'—a short distance into the mold cavity until the brush is forced from its seat in the base-plate.

The plunger may be of the exact length to just fill the aperture, having its ends flush with the respective surfaces of the base-plate. When so formed, the plunger can be operated by a small follower-pin, or in any known manner.

By projecting the lower end of the plunger below the bottom surface of the base-plate, as shown at D³—, the projection is easily accessible, and the plunger can be driven into the mold cavity by means of a hammer or

other implement applied thereto, or by applying the base-plate to any plane surface.

The plunger may be of uniform diameter throughout; but I prefer to make the lower end of the plunger of a smaller diameter than the molding end, and the plunger-aperture in the base-plate similarly contracted to form a flange or seat D⁴— for the enlarged portion of the plunger, whereby the molding face of the plunger is supported in proper position against the internal mold-pressure, when in use, independently of any external support for the base-plate itself.

In molding brushes, it is difficult to remove the bristle-supporting end of the brush from the mold, due to the knots of bristles tightly fitting in the recesses in the base-plate. I therefore locate one or more of my improved plungers in apertures formed in the recessed end of the plate.

The molding face of the plunger may be made of any desired size by locating one or more of the bristle-recesses in the plunger, as shown at D⁵—.

The number and position of the plungers may be varied according to the quality of the composition employed, or the style of article formed therefrom.

I am aware that a mold for casting metal has been provided with a plurality of plungers for removing the casting from the mold, and I make no claim to such a device broadly.

It is well known to those skilled in the art of making molded brushes, that great difficulty is experienced in removing the molded brush from the base-plate of the mold. This is largely due to the fact that the plastic composition is subjected to extreme pressure in the mold, which pressure forces the composition so tightly between and around the bristles in the upper portions of the recesses in the base-plate, as to cause the bristles to become wedged tightly by the composition within the recessed portion of the mold.

As heretofore practiced, it has been customary to construct a brush-mold in three parts or sections, the middle plate or section having an aperture for the bristle-receiving portion of the base-plate, and the walls of the

aperture being chamfered along their upper edges so as to underlie the periphery of the head-portion of the molded brush, and serve as a lifting device for withdrawing the bristles from the recesses.

By reason of the extreme pressure, every

joint in the mold forms a fillet or rib on the molded article, which must be removed after the article is taken from the mold; and it will readily be seen that the use of a middle plate underlying the edge of the brush-head produces a fillet along the edge of the under face of the brush-head in close proximity to the bristles and in a position which renders its removal difficult without cutting or injuring the bristles.

By providing the base-plate with one or more plungers in its bristle-receiving portion where the greatest resistance to the withdrawal of the brush occurs, I am able to wholly dispense with the middle-plate or section formerly employed, the crown-plate and base-plate being together adapted to wholly form the mold cavity, with a single joint or line of division. I am therefore able to avoid the formation of a fillet on the under face of the brush-head, except such as is formed by the plunger, which is not conspicuous, and is concealed by the surrounding bristles, rendering its removal unnecessary.

The only fillet requiring removal is that which marks the dividing line between the base and crown-plates, and which is on the extreme edge of the brush, in a position to be easily and safely removed.

The bunches of bristles are so closely located that a plunger of a size adapted to be inserted between two neighboring recesses would present a face of such small area as to be likely to chip or break the hardened and brittle composition. By forming one or more of the bristle recesses in the plunger itself, the plunger-face can be made of any desired area, insuring the safe removal of the brush from the mold.

What I claim as new, and desire to secure by Letters Patent, is—

In a brush-mold, the combination with the crown-plate, of a base-plate provided with bristle-recesses and a plunger-aperture extending through the recessed portion of the plate, and a plunger fitting and movable through the aperture and provided with a bristle-recess, substantially as described.

In testimony whereof I have hereunto set my hand this 15th day of June, 1894.

WILLIAM MORRISON.
